Primary Examiner — Holly Baynham(74) *Attorney, Agent, or Firm* — Ross Barnes LLP; Monty L Ross; Robin L. Barnes(57) **CLAIM**

The ornamental design for a carabiner wire-gate, as shown and described.

DESCRIPTION

FIG. 1 is a front elevation with the wire-gate in a closed position;

FIG. 2 is a rear elevation with the wire-gate in an open position;

FIG. 3 is a top plan view;

FIG. 4 is a right side elevation view;

FIG. 5 is a left side elevation view; and,

FIG. 6 is a bottom plan view.

The broken lines showing a carabiner are for the purposes of illustrating environment and form no part of the claimed design.
